UNITED STATES PATENT OFFICE.

REID B. GRAINGER, OF REDONDO BEACH, CALIFORNIA, ASSIGNOR TO ELLIOTT CORE DRILLING COMPANY, A CORPORATION OF CALIFORNIA.

CORING DEVICE.

Application filed June 1, 1927. Serial No. 195,638.

My invention relates to coring devices of the double barrel type wherein flushing fluid is used during the drilling operation.

In using coring devices of the type referred to, circulating fluid under pressure is discharged to the cutting level through the drill. Consequently, the hole is partially filled with this fluid, the heavier portion of which settles to the bottom of the hole between coring operations. As the drill is lowered into the hole, the fluid enters the inner or core barrel proper which becomes filled with the fluid. To permit exit of this fluid from the core barrel, such barrels are usually provided with a valve mounted on the upper end of the core barrel and so arranged that, as the core enters the core barrel, the fluid above the core is discharged through the valve ordinarily against the pressure of the flushing fluid.

The principal object of my invention is to provide an attachment for the upper end of the core barrel, of simple form and construction which is so constructed as to cause the circulating fluid to produce an aspirating effect on the fluid being discharged from the core barrel, thereby relieving the pressure in the core barrel and resulting in an unobstructed entrance of the core into the barrel.

Other objects and advantages will readily appear to those skilled in the art from the following description and the accompanying drawings.

Referring to the drawings which are for illustrative purposes only—

Fig. 1 is a vertical sectional view of a core drill, embodying a form of my invention.

Fig. 2 is a sectional plan view on line 2—2 of Fig. 1.

Fig. 3 is a sectional plan view on line 3—3 of Fig. 1.

Fig. 4 is a side elevation of the upper end of the core barrel.

The drill shown is of the rotary type and consists generally of an outer barrel 11, the upper end of which is connected to the lower end of the tubing 12 through which the drill is rotated. The lower end of the outer barrel 11 is threaded into the drill body 13, which is provided with cutting blades 14 and 15, and which terminates in an annular cutter 16, surrounding a central opening 17 which receives the core,

Threaded with the body 13 is an inner or core barrel 18, which is spaced apart from the outer barrel 11, thereby forming an annular passage 20, through which the flushing fluid is circulated downward and out through discharge openings 21 formed in the drill body 13. Threaded into the upper end of the core barrel 18 is a hollow head 22, provided with a perforated plate 23 for preventing the core or large cuttings clogging the valve 24.

The valve 24 operates in a cage 25 which is threaded into the upper part of the head 22, extending upwardly therefrom to support a hood 27 threaded onto the upper end of the cage 25.

The upper end of the head 22 is tapered inwardly and upwardly under the skirt 28 of the hood 27 which skirt, at its inner lower edge, is correspondingly tapered and spaced apart from the tapered portion of the head, thereby forming a downwardly discharging annular passage 30 therebetween, for the purpose hereinafter described.

It is also to be noted that the exterior of the head 22 is tapered downwardly and outwardly giving the effect of a nozzle to the circulating fluid passing downwardly past the discharge opening 30.

It is to be understood that the drill is operated in the usual manner, in so far as the drill proper is concerned, and that during the drilling operation the core enters the core barrel forcing any accumulation above the core in the barrel through the valve 24 and out through the cage 25, which, with a drill as ordinarily constructed, such material passing through the valve is against the pressure of the circulating fluid.

In using a device as above described, embodying my invention, this material is discharged from the cage 25 under the hood 27, and is discharged downwardly through the annular passage 30. Due to the aspirating effect of the circulating fluid under considerable pressure passing downwardly entirely around the discharge passage 30, the pressure in the cage is relieved thereby permitting the valve 24 more readily to unseat, resulting in a relieving of the pressure in the core barrel and a consequent diminishing of the resistance in the core barrel to the core, and the obtaining of a core more proportionate in length to the depth of strata actually drilled through.

What I claim as my invention is:

1. In combination, a core drill having an inner and outer barrel forming a passage therebetween for circulating fluid, a valve at the upper end of the inner barrel, and means for forming an annular discharge outlet for said valve, discharging into the circulating fluid passage. 45
2. In combination, a core drill having an inner and outer barrel forming an annular passage therebetween for circulating fluid, a head on the upper end of said inner barrel, a valve in said head, and means cooperating with said head independent of said barrel forming therewith an annular discharge outlet for said valve into said fluid passage. 50
3. In combination, a core drill having an inner and outer barrel forming an annular passage therebetween for circulating fluid, a head on the upper end of said inner barrel, a valve in said head, and means cooperating with said head independent of said barrel forming therewith an annular downwardly and outwardly diverging discharge outlet for said valve into said fluid passage. 55
4. In combination, a core drill having an inner and outer barrel forming an annular passage therebetween for circulating fluid, a head on the upper end of said inner barrel, a hood over said valve having its lower end spaced apart from said head to form an annular discharge opening for said valve into said fluid passage. 60
5. In combination, a core drill having an inner and outer barrel forming an annular passage therebetween for circulating fluid, a head on the upper end of said inner barrel, a hood over said valve having its lower end spaced apart from said head to form an annular downwardly and outwardly diverging discharge opening for said valve into said fluid passage. 65
6. In combination, a core drill having an outer and an inner barrel spaced apart to form a circulating fluid passage therebetween; a head on the upper end of said inner barrel, a valve, a cage for said valve on said head, and a hood supported on said cage having its lower edge spaced apart from said head to form an annular discharge opening therebetween. 70
7. In combination, a core drill having an outer and inner barrel spaced apart to form a circulating fluid passage therebetween; a head on the upper end of said barrel terminating at its upper end in an inwardly and upwardly tapered portion, a valve, a cage for said valve mounted on said head and a hood mounted on said cage having its lower inner tapered correspondingly to the tapered portion of said head and spaced apart therefrom, to form an annular discharge opening for said valve. 75
8. In combination, a core drill having an outer and inner barrel spaced apart to form a circulating fluid passage therebetween, a head on the upper end of said barrel terminating at its upper end in an inwardly and upwardly tapered portion, a valve, a cage for said valve mounted on said head and a hood mounted on said cage having its lower inner edge tapered correspondingly to the tapered portion of said head and spaced apart therefrom, to form an annular discharge opening for said valve, said hood having its outer face tapered outwardly and downwardly toward its lower end to form, with the outer barrel, an annular nozzle about the discharge opening from said valve. 80

In testimony whereof, I have hereunto set my hand at Los Angeles, California, this 27 day of May, 1927.

REID B. GRAINGER.
